CLAIM

The ornamental design for a bipolar forceps, as shown and described.

DESCRIPTION

FIG. 1 is a perspective view of the bipolar forceps;
 FIG. 2 is a front view of the bipolar forceps;
 FIG. 3 is a right side view of the bipolar forceps, the left side view being a mirror image thereof;
 FIG. 4 is a rear view of the bipolar forceps;
 FIG. 5 is a top view of the bipolar forceps; and,
 FIG. 6 is a bottom view of the bipolar forceps.
 The broken lines shown in the figures are included for the purpose of illustrating portions of the bipolar forceps and form no part of the claimed design.
